STRAND PACKAGE ARBOR

Ernest K. Bauer, Meadville, Pa., assignor to American Viscose Corporation, Wilmington, Del., a corporation of Delaware

Application March 23, 1950, Serial No. 151,475

10 Claims. (Cl. 242—46.2)

1

This invention relates to a tube holder or arbor for supporting the packages of strand wound about an annular core, particularly to a rotatable support upon which the package may be secured and centered with respect to its axis of rotation.

It is an object of the invention to provide a holder having a rigid spindle structure such that the rotatable portion may revolve freely without vibration. It is another object to provide a holder on which the package may be centered and secured to a position wherein it is restrained from moving or tilting relative to the holder. It is still another object to provide a package arbor which has a spindle or shaft of unitary construction. Other objects, features and advantages of the invention will be apparent from the description of the invention relating thereto in which:

Fig. 1 is a longitudinal section taken along the axis of apparatus according to one embodiment of the invention;

Fig. 2 is an end view of the apparatus illustrated in Fig. 1;

Fig. 3 is a section view taken along line III—III of Fig. 1;

Fig. 4 illustrates a spring member of Fig. 1 viewed from another direction;

Fig. 5 is a section view along the axis of a modified apparatus;

Fig. 6 is a section view taken along line VI—VI of Fig. 5;

Fig. 7 is an end view of a manual control element of the apparatus of Fig. 5;

Fig. 8 is a longitudinal section of modified apparatus taken along its axis; and

Fig. 9 is an end view of the apparatus illustrated by Fig. 8.

In brief, an arbor or rotatable package support according to the invention comprises a unitary spindle, an annular rotary housing supported on the spindle by bearings, spring mounted gripping members for engaging the inner surface of an annular strand package to the outer wall of the housing, and a cam controller for engaging surfaces of the springs to urge the gripping members into engagement or out of engagement with the package, and a portion of the controller extending axially from one end of the housing to make it accessible for manual manipulation.

Fig. 1 illustrates in section an assembly which may be readily mounted on a twister or other winding device by insertion of the left end of a spindle 12 into a cylindrical socket (not shown) slotted to accommodate a pin 14. A cylindrical sleeve or housing 15 is supported rotatably with respect to the shaft by anti-friction bearings 17

2

and 18 the inner races of which are secured to the spindle by set screws 19 and 20. Annular spacer or hub members 24 and 25 center and support the housing 15 on the outer races of the bearings. Three leaf-type spring members 28 are secured by rivets 29 to extend lengthwise of the sleeve to sections of the inner surface of the sleeve 15 120° apart. Fig. 4 illustrates a spring member 28 as seen when viewing the member in a 10 radially outward direction from the axis of the assembly. The springs 28 have apertures 30 in which to secure blocks 32 comprising material such as a soft vulcanized rubber composition. The blocks 32 are each supported along a radius 15 extending from the axis of the shaft 12 through holes 33 provided through arcuately spaced sections of the housing 15 to engage the inner surface of a rigid core 34 of a strand package. The end portions which support the blocks 32 deflect 20 radially outwardly to urge the blocks against the core surface. Thus, a package 35 is supported by the assembly on the blocks 32 and on the surface of a flared flange 38.

To release the grip of the blocks 32 on the 25 package core 34, a cam member 36 best illustrated in Fig. 3, may be moved in an axial direction within the housing to produce deflection of the springs. Sections 37 of the springs are biased in a radial outward direction toward the left as viewed in Fig. 1 to produce cam surfaces 30 on which the member 36 may work. Movement of the cam member 36 to the right causes the peripheries of apertures 46 of the member to slidably engage the outer surface of the springs 35 whereby the blocks are carried radially inwardly and away from the core surface. The cam member is connected by three parallel rods 39 to a manual control member 40 spaced axially from the cam member and the outer surface of the bearing 25. The control member is provided with a sleeve element or handle 42 having an outer knurled surface with which to grip the member 40. Thus by manual manipulation of the member 42, the position of the cam member 36 may be 40 varied in a direction lengthwise of the springs 28 to obtain radial movement of the blocks 32. The sections 37 of the springs are provided with surfaces 44 which are substantially parallel to the cylindrical wall of the sleeve 15 so that the 45 cam member 36, when pulled into the position for producing disengagement of the blocks, will remain in that position until forcibly moved toward the right as viewed in Fig. 1.

Fig. 5 illustrates a modification of the device 50 shown in Figs. 1 to 4 wherein a sleeve or shroud

^{15a} is supported on the shaft ¹² in the manner shown for the sleeve ¹⁵ of Fig. 1 except that the left bearing ^{17a} is spaced further inward from the left end of the sleeve ^{15a}. A spacer member which supports the sleeve on the outer race of the bearing ^{17a} is apertured to permit extension therethrough of two leaf-type springs ⁵⁰. As viewed in Fig. 5, the left ends ⁵¹ of the springs engage the inner surface of the sleeve ^{15a}; the springs are set or formed, and the apertures ⁴⁸ of the spacer member are positioned at sufficient radius, so as to deflect the portions of the springs extending to the right from the apertures toward the inner surface of the sleeve. Thus the springs are strongly inclined to urge the resilient cushions ⁵³ fastened thereto in a direction radially outwardly to a position wherein they extend through apertures ⁵⁴ through the sleeve ^{15a} against the inner surface of a strand package (not shown) surrounding the sleeve ^{15a}. The right end portions of the springs are contoured to provide cam surfaces ⁵⁶ by which the springs may be engaged by a cam member ⁵⁵ and deflected toward the shaft ¹² to carry the cushions ⁵³ out of engagement with the inner surface of a strand package. The cam member ⁵⁵ is centrally apertured, as shown in Fig. 6, to accommodate the shaft ¹² and to provide cam surfaces ⁵⁷. The member ⁵⁵ may be moved in a direction parallel to the shaft toward and away from the inner bearing race ⁵⁸. The cam member ⁵⁵ is connected to a handle, also illustrated in Fig. 7, comprising a disc element ⁶⁰ and a tubular element ⁶¹ by two spacer rods ⁶⁴ extending between and secured to the cam member and the element ⁶⁰. The hub member ⁶² is apertured to permit extension therethrough and movement relative thereto of the rods ⁶⁴.

Fig. 8 illustrates a strand package holder in which engagement and disengagement of a plurality of cushions ⁷⁰ with the inner surface of a strand package surrounding the sleeve ^{15b} is effected by a rotatable cam member ⁷² instead of by axially slideable cam members such as employed in the embodiments described earlier herein. The sleeve ^{15b} is supported on two anti-friction bearings ⁷⁵ and ⁷⁶. An annular hub ⁷⁸ which supports and centers the left end portion of the sleeve ^{15b} on the outer race of the bearing ⁷⁵ is provided also with a flange ⁷⁹ to receive the edge of a package core to positively position the package in an axial direction with respect to the arbor. The cushions ⁷⁰ are each supported by leaf-type springs ⁷¹ which are secured to the sleeve by the rivets ⁷³. The springs extend almost to the right end of the sleeve ^{15b} as viewed in Fig. 8. The outer diameter of the cam member ⁷² is slightly less than that of the inner surface of the sleeve member so as to be freely rotatable within the sleeve member; an aperture ⁸¹ through the member prevents contact thereof with the shaft ¹². Handles ⁸³ extending from the cam member enable manual rotation thereof with respect to the sleeve ^{15b} and the end portions of the springs. As shown in Fig. 9, the cam is in the position permitting maximum outward deflection of the springs ⁷¹ and engagement of the cushions ⁷⁰ with the inner surface of a strand package when supported by the arbor. The cam member ⁷² is rotated from this position in a counterclockwise direction to bring the surfaces ⁸⁵ into engagement with the outer surfaces of the springs ⁷¹ when desired to move the cushions ⁷⁰ radially inward to release a package.

While preferred embodiments of the invention have been shown and described, it is to be under-

stood that changes and variations may be made without departing from the spirit and scope of the invention as defined in the appended claims.

I claim:

1. A holder for annular strand packages comprising a shaft, a sleeve member supported by the shaft in rotatable and coaxial relationship therewith, the member having an opening disposed intermediately of its ends, a movable element of smaller cross section than the opening for engaging a package supported around the member, spring means for supporting the movable element in the opening, said element being attached to the spring means and the spring means being secured to the member at a point remote from the point of attachment to the element, the spring means having a cam portion which is remote from the portion of the spring means secured to the member, a cam for engaging the cam portion, said cam being supported within the member in slideable adjustable relationship with a guide surface of the member, and means for adjusting the cam extending in an axial direction independently, and radially exteriorly of, the shaft from the cam to a manually accessible region at one end of the member.

2. A holder for annular strand packages comprising a shaft, a sleeve member supported by the shaft in rotatable and coaxial relationship therewith, the member having an opening disposed intermediately of its ends, a movable element of smaller cross section than the opening, a spring for supporting the element, the spring being supported within the member in non-rotatable relationship therewith and having the element attached thereto for the purpose of supporting the element in alignment for movement through the opening, the spring being arranged and tensioned to urge the element in a radially outward direction through the opening, said spring having a cam portion, a cam for engaging the cam portion, said cam supported within the member in slideable adjustable relationship with a guide surface of the member, and means for adjusting the cam extending in an axial direction independently, and radially exteriorly of, a shaft from the cam to a manually accessible region at one end of the member.

3. A holder for annular strand packages comprising a shaft, a sleeve member supported by the shaft in rotatable and coaxial relationship therewith, the member having a plurality of openings which extend in a radial direction through portions of the member that are angularly spaced from each other with respect to the axis of the member, movable elements of smaller cross section than the openings for engaging a package supported around the member, spring means for supporting the movable elements in the openings, said elements being attached to the spring means and the spring means being secured to the member by portions of the spring means remote from the points of attachment to the elements, the spring means having cam surfaces which are remote from said portions of the spring means secured to the member, a cam for engaging the cam surfaces, said cam being supported within the member in slideable adjustable relationship with a guide surface of the member, and means for adjusting the cam extending in an axial direction independently, and radially exteriorly of, the shaft from the cam to a manually accessible region at one end of the member.

4. A holder for annular strand packages com-

prising a shaft, a sleeve member supported by the shaft in rotatable and coaxial relationship therewith, said member having a plurality of openings which extend in a radial direction through portions of the member that are angularly spaced from each other with respect to the axis of the member, movable elements of smaller cross section than the openings, a plurality of spring supported within the member in non-rotatable relationship therewith, each spring having one of said elements attached thereto for the purpose of supporting the element in alignment for movement through an opening, the springs being arranged and tensioned to urge the elements in a radially outward direction through respective openings, 15 cam surfaces on the springs which face radially outwardly, a cam for engaging the cam surfaces, said cam being supported within the member in slideable adjustable relationship with a guide surface of the member, and means for adjusting the cam extending in an axial direction independently, and radially exteriorly of, the shaft and from the cam to a manually accessible region at one end of the member.

5. A holder for annular strand packages comprising a shaft, a sleeve member, a pair of bearings for supporting the member concentrically and rotatably with respect to the shaft, the bearings being spaced within the member adjacent the ends thereof, at least one opening through a portion of the member disposed between the bearings, a leaf spring extending longitudinally within the member, being fixedly secured within the member, and having a cam follower section, an element for engaging the interior surface of packages mounted on the spring for movement through said opening, a cam for engaging the cam follower section, and means connected with the cam and extending through one of the bearings into a manually accessible region adjacent one of the ends of the sleeve member for moving the cam in an axial direction.

6. A holder for annular strand packages comprising a shaft, a sleeve member supported by the shaft in rotatable and coaxial relationship therewith, the member having a plurality of openings which extend in a radial direction through portions of the member that are angularly spaced from each other with respect to the axis of the member, movable resilient elements of smaller cross section than the openings, spring means supported within and secured to the sleeve for supporting said elements in alignment for movement through the openings, the spring means being mounted and tensioned to urge the elements in a radially outward direction through the openings, radially outwardly-facing cam surfaces on the spring means, a cam for engaging the cam surfaces enclosed within and supported by the sleeve in adjustable rotatable relationship with a guide surface of the sleeve, and manual gripping means for adjusting the cam extending axially from the cam to a manually accessible region at one end of the sleeve.

7. A holder for annular strand packages comprising a shaft, a sleeve member supported by the shaft in rotatable and coaxial relationship therewith, the member having a plurality of openings which extend in a radial direction through portions of the member that are angularly spaced from each other with respect to the axis of the member, movable elements of smaller cross section than the openings, spring means secured to and supported within the sleeve for supporting said elements in alignment for movement through

10 the openings, said spring means being mounted to urge the elements in a radially outward direction through the openings, cam surfaces on the spring means which face radially outwardly and extend in a direction which is longitudinal of the sleeve, a cam for engaging the cam surfaces, said cam being slidably adjustable in a longitudinal direction with respect to the sleeve along a guide surface thereof, and means for adjusting a cam extending from the cam to a manually accessible region at one end of the sleeve.

8. A holder for annular strand packages comprising a shaft, a sleeve member, spaced bearings for supporting the sleeve member in coaxial and rotatable relationship with the shaft, the member having a plurality of openings which extend in a radial direction through portions of the member that are angularly spaced from each other with respect to the axis of the member, a plurality of elongate leaf springs each secured by one end thereof to arcuately spaced sections of the inner surface of the sleeve which are spaced from the openings in a direction parallel to the shaft, said springs having apertures in radial concurrence with the openings in the sleeve, a resilient cushion of smaller cross section than the openings extending through each opening and secured to the adjacent spring through the aperture thereof, said springs being tensioned to urge the cushions 25 through the openings, sections of similar contour in each of the spring members intermediate the aperture and the secured end-portion which are contoured to provide a cam surface extending longitudinally of the sleeve, an annular cam member fitting slidably within the inner surface of the sleeve and having a cam surface for engaging the cam surface of each spring, a manual control member supported for movement in a direction parallel to the shaft in a manually accessible region adjacent the end of the sleeve, and symmetrically disposed axially extending push rods for connecting the cam member and the control member.

9. A holder for annular strand packages comprising a shaft, a sleeve member, the member having a plurality of openings which extend in a radial direction through portions of the member that are angularly spaced from each other with respect to the axis of the member, a pair of spaced bearings for supporting the sleeve member in rotatable and coaxial relationship with the shaft, an annular spacer member between the outer race of one of the bearings and the sleeve, the spacer member having apertures extending therethrough in a direction parallel to the shaft with the angular spacing of the apertures being the same as that of the openings, a plurality of elongate leaf springs extending longitudinally within the sleeve with their end-portions extending 30 through the apertures beyond the spacer member to engage the inner surface of the sleeve at a point intermediate the bearing and the end of the sleeve, the major portion of each spring extending from the spacer member toward the other bearing, said springs terminating in similar cam surfaces aligned in the longitudinal direction of the springs, an aperture through each of the springs in radial alignment with a sleeve opening and located between the annular spacer member and the cam surface, resilient cushions secured in said apertures and extending through the openings, an annular cam member having uniform apertures spaced angularly about the axis to receive the cam sections of the springs, 35 said cam member having a slightly smaller di-

diameter than the inner surface of the sleeve within which the member is supported in sliding contact, another annular member contained slidably within the end-portion of the sleeve adjacent the second-named bearing and a coaxial tubular handle secured thereto, and push rods connecting the cam member and the last-named annular member.

10. A holder for annular strand packages comprising a shaft, a sleeve member, spaced bearings, one bearing adjacent each end of the sleeve, for supporting the sleeve in rotatable and coaxial relationship with the shaft, the member having a plurality of openings which extend in a radial direction through portions of the member that are angularly spaced from each other with respect to the axis of the member, a like number of elongate leaf springs being similarly angularly spaced and having end-portions secured to sections of the inner surface of the sleeve and extending longitudinally therewithin into radial alignment with the openings, said springs extending also through apertures provided in the outer section of the bearing most remote from the secured ends of the springs, cushions secured to 15 respective portions of each of the springs in

5

10

20

25

radial alignment with the openings, each of said springs being tensioned to urge the cushion supported thereon through an opening, an annular cam member having a plurality of similar cam surfaces spaced in agreement with the angular spacing of the springs and extending in a plane normal to the axis, said cam member being adjustably rotatable with respect to, and within, the end-portion of the sleeve to deflect all of the springs and cushions radially-inwardly simultaneously, said cam member being secured in an axially-extending direction between the apertured bearing section and a crimped edge of the sleeve.
